UNITED STATES PATENT OFFICE

MARVIN B. LEVY, OF LINCOLN, NEBRASKA

MEMO DESK MACHINE

Application filed June 27, 1930. Serial No. 464,276.

My invention relates to memo desk machines designed for use on the desk or counter for preparing bills, memoranda or the like in original form and for simultaneously preparing a copy on a separate roll of paper which may be rolled up for record purposes, the original copy being adapted to be torn from the roll to be presented to the customer or to be filed.

10 One of the objects of the invention is the provision of a machine of the character specified, the machine being constructed for convenience in making both the original and the carbon copies and in rolling up the record or carbon copy so that it will be available for reference.

15 The primary object of the machine is the provision of a feed mechanism for positively delivering the original copy and of means for rendering the feed mechanism inoperative at will so that the record copy may be unrolled in order that the record may be inspected without disturbing the roll on which the original copy is made.

20 25 Having in view these objects and others which will be pointed out in the following description, I will now refer to the drawings, in which

Figure 1 is a view in perspective of the machine, portions being torn or broken away in order to disclose interior parts.

Figure 2 is a view in lengthwise section of the machine.

Figure 3 is a view in side elevation of the gear train.

The casing of the machine consists of two side plates 10 connected by a front member 11. The forward portion of the machine is shallow and flat while the rear portion is relatively deep both for the purpose of receiving the various rollers and paper strips and also for convenience when it is desired to consult the record. The rear portion of the frame is covered by a lid 12 which projects downwardly at its rear to cover the rear end of the frame as well as the top portion thereof. The lid 12 is hinged at 13 to the frame. The forward end 14 of the lid 12 projects downwardly into the frame, being immediately in the rear of a deflector 15

which is rigidly secured to the side walls 10 of the frame. The shield 16 is also a part of the frame, being connected thereto immediately underneath the flanges of the side walls. In addition to these frame parts there is also a table or platform 17 which is also connected to the side walls. The frame is supported on rubber or other elastic feet 18 which are secured to inwardly directed flanges from the side walls of the frame.

55 60 The record copy is made on a sheet of paper 19 which unrolls from a spool 20 and which rolls on to a spool 21, these spools having shafts 20' and 21' respectively. From the spool 20 the strip of paper 19 passes under an idle roller 22, then between the two forward idle rollers 23 and 24, over the table 17, then downwardly under the idle roller 22 and finally rearwardly and upwardly to the roller 21. The strip in passing over the table 17 is 65 always in close contact with the table. The shaft of the roller 21 is provided with a knob 25 at the right-hand side of the frame and it is apparent that the paper may be rolled on to the spool 21 by turning the knob 25 in the proper direction. As the strip 19 is wound on to the spool 21 it is unwound from the spool 20 and it is dragged over the table 17.

70 75 The original copy is made on the strip of paper 26 which is delivered from the spool 27 on the shaft 27'. The strip 26 also passes between the rollers 23 and 24, thence over the table 17 and finally between the rollers 28 and 29. As the free end of the paper passes between the rollers 28 and 29 its edge comes in 80 contact with the deflector plate 15 which forces it out through the opening in the top of the casing. The paper delivered from the spool 27 is preferably carbonized paper or paper which is backed with a material for 85 making a carbon or similar impression on the surface of the strip 19.

90 95 In order to make the feed of the strip 26 positive, it is necessary to provide suitable gearing which forces the strip 26 to travel with the strip 19. This gearing, which is encased within a housing inside of the frame, is best shown in Figure 3. It consists of a driving gear 30 which is secured to the shaft of the roller 21. The turning of the knob 25 100

will thus cause the turning of the gear 30. Also secured to the shaft of the spool 21 is a pivoted lever 31 which carries an idle gear 32 meshing with the gear 30. The lever 31 is at the left-hand side of the frame and it is provided with a handle 33 which may be depressed or elevated by pressing down with the thumb or by lifting up. Since the axis of the gear 32 is concentric at all times with the axis of the gear 30, these two gears will always be in mesh regardless of the position of the handle 33. The gear train includes also three idle gears 34, 35 and 36, all of which have fixed bearings in the frame of the machine. The gears 32 and 34 are in mesh with each other when the handle 33 is in its uppermost position but it will be apparent from an inspection of Figure 3 that the depression of the handle 33 will force the idle gear 32 out of mesh with the idle gear 34. The gear 35 is secured to the shaft of the roller 28 while the gear 36 is secured to the shaft of the roller 29. When the gears 32 and 34 are in mesh, the rollers 28 and 29 will be rotated in opposite directions to force the strip 26 through between them. In order to facilitate the engagement of the rollers 28 and 29 with the strip of paper, the spindles or shafts of the rollers 29 are provided with spring pressed bearing blocks 37 which hold the two rollers in tight contact and the roller 28 is provided with a knurled or roughened surface at 38. The strip 26 will thus be held tightly between the two rollers 28 and 29 and it must pass through 35 between them as through the rollers of a wringer.

In use, the original copy is made on that portion of the surface shown at 39 in Figure 1. Since the under surface of the strip of paper has a recording coating, a record copy will be produced on the surface of the strip 19 immediately below the portion 39. The knob 25 is then turned to wind the strip 19 on the spool 21. The turning of the knob 25 sets in motion the gear train shown in Figure 3 and forces the free end portion of the strip 26 to pass through between the rollers 28 and 29 to be fed outwardly from the machine. At this point the end portion of the strip 26 containing the memoranda or bill is torn off, the shield 16 being provided with a cutting edge to facilitate the tearing of the strip 26.

One of the chief drawbacks of machines of this general class is that it is impossible to consult the record without great inconvenience such as removing the spool containing the record. In the present instance this difficulty is avoided by making all of the parts conveniently accessible for consulting the record. When the lid 12 is thrown back on the hinge 13 it exposes a large portion of the surface of the record copy, most of the surface between the spool 21 and idle roller 22 being visible. The spindle of the spool 20 is provided with a knob 40 whereby the strip

19 may be wound on to the spool 20 and unwound from the spool 21. Before this is done, however, the handle 33 should first be depressed in order to throw the idle gears 34, 35 and 36 out of mesh. The turning of the knob 40 will then turn the two rollers 28 and 29. These rollers, however, are so constructed that they will firmly hold the strip 26 against movement while the strip 19 is moving. For consulting the record it is only necessary to lift the lid 12, to depress the handle 33 and to unwind the strip 19 by turning the knob 40 until the desired record is in the line of vision. In order to bring the strip 19 back into position where the next record is to be made it is only necessary to turn the knob 25 and to thus rewind the strip 19 on to the spool 21 to the desired position.

Certain features also make the machine "fool proof". In making original and record copies it is necessary only to turn the knob 25 with the gearing in the position shown in Figure 3. If, however, the knob 40 were accidentally or carelessly turned while the idler is in mesh, it might cause an unwinding of the strip 19 such as to result in the tearing or tangling of the strip. The turning of the knob 40 would produce a tension on the strip 19 in the direction opposite the winding direction. Due to the arrangement of the gears 30 and 32 a movement of the gear 30 in the reverse direction will almost instantly force the gear 32 out of mesh with the gear 34.

Having thus described my invention in such full, clear and exact terms that its construction and operation will be readily understood by others skilled in the art to which it pertains, what I claim as new and desire to secure by Letters Patent of the United States is:

1. A memo desk machine having a writing table, means for supporting a pair of superposed strips of paper movable over the surface of said table whereby the lower of the strips may receive a carbon record of the writing on the upper of the strips, means under the control of the operator for moving the lower of the strips over said table, means positively engaging the upper of the strips of paper, connections between said two means for positively feeding the upper of the strips when the lower of the strips is being moved over said table, and means for disconnecting said connections whereby said engaging means will hold the upper of the strips against movement when the lower of the strips is moved in either direction.

2. A memo desk machine having a writing table, means for supporting a pair of superposed strips of paper movable over the surface of said table whereby the lower of the strips may receive a carbon record of the writing on the upper of the strips, means under the control of the operator for moving the lower of the strips in either a forward

or a reverse direction over said table, a pair of parallel rollers for engaging the upper of the strips, a gear train connecting said rollers with said means for moving the lower of the strips whereby the upper of said sheets is moved forward simultaneously with the forward movement of the lower of the strips, said gear train including an idler movable into and out of mesh in said gear train, the position of the axis of said idler being out of alignment with the axes of the intermeshing gears whereby it will be automatically thrown out of gear under the reverse movement of the lower of the strips.

5 with the delivery end portion of the upper of said sheets, a gear train between said rollers and one of said spools whereby the rotation thereof is communicated to said rollers for advancing the upper of the strips in 70

10 unison with the forward movement of the lower of the strips, and finger operated means for unmeshing said gear train whereby the lower of the strips may be wound on either of said spools while the upper of the strips 75 is held stationary.

In testimony whereof I affix my signature.
MARVIN B. LEVY.

15 3. A memo desk machine including a writing table, means for supporting a pair of superposed strips of paper movable over the surface of said table whereby the lower of the strips may receive a carbon record of

20 the writing on the upper of the strips, a pair of spools supporting the lower of the strips at the opposite extremities thereof whereby the lower strip may be wound on either of said spools and unwound from the other,

25 means engaging the upper of the strips at the delivery end thereof, and means interposed between one of said spools and said engaging means for causing the movement of said spool to be communicated to said engaging means to move the two strips in unison over said table, and finger actuated means for rendering said interposed means inoperative whereby the lower of the strips may be wound on either of said spools while

30 35 the upper of the strips is held stationary.

4. A memo desk machine including a writing table, means for supporting a pair of superposed strips of paper movable over the surface of said table whereby the lower of the strips may receive a carbon record of

40 the writing on the upper of the strips, a pair of spools supporting the lower of the strips at the opposite extremities thereof, a pair of rollers in clamping engagement with the delivery end portion of the upper of the strips, a gear train between said rollers and one of said spools whereby the rotation thereof is communicated to said rollers for advancing the upper of the strips in unison

45 with the forward movement of the lower of the strips, and means for unmeshing said gear train on the reverse movement of the lower of the strips whereby said rollers will function to prevent movement of the upper

50 of the strips when the lower of said sheets is moving in a reverse direction.

5. A memo desk machine including a writing table, means for supporting a pair of superposed strips of paper movable over the surface of said table whereby the lower of the strips may receive a carbon record of the writing on the upper of the strips, a pair of spools for supporting the lower of the strips at the opposite extremities thereof, a pair of rollers in clamping engagement
